ELEVATOR

Ernest L. Gale, Yonkers, N. Y.

Application March 25, 1932, Serial No. 601,081

75 Claims. (Cl. 187—29)

My invention relates to elevators and more particularly to a mechanical system to control a plurality of elevators operating in a bank.

There are at the present time various types of 5 electrical systems identified in the trade as signal control used for the purpose of controlling slow-down contactor circuits instead of flash contactor circuits as commonly used in the signal art, for a bank of elevators from a single riser of up and 10 down landing buttons to initiate slow-down and stop of the first car reaching a pre-determined distance from any landing for which a call is registered, and whose direction of movement corresponds to such registered call. Push-but- 15 tons within each car, one for each landing served are actuated by a car operator to pre-register calls announced by car passengers and they initiate slow-down of the car with which they are associated. These systems are primarily elec- 20 trical in structure and function as to the passenger controlled floor-relays or call registering means having contacts which operate jointly with car controlled electrical commutating machines called selectors to control electrical secondary 25 circuits to initiate operation of slow-down mech- anism.

The present invention accomplishes substantially the same results as does the electrical type referred to, but it is of a mechanical type as to 30 the call registering means, car controlled selectors, re-set means for said call registering means, and also as to certain other features. The elements taken by themselves and in combination are new in the art and have a mode of operation 35 differing very substantially from the electrical type now in public use or any patented prior art pertinent thereto regardless of type.

A summation of the various features of the present invention follows:—first, selectively con- 40 trolled mechanical devices, one up and one down for each intermediate landing served, responsive to up and down hall-buttons constructed and arranged to register calls common to all the cars of the bank, by the use of only a single up 45 and a single down actuating magnet therefor, and arranged so that calls initiated from the respective cars are registered only for the particular car or cars from which the call is initiated so that in effect a hall-button will cause stop of 50 a first car of the bank at its landing, whose direction corresponds to said button, while on the other hand the car buttons cause stop only of their own car; second, a mechanical selector actuated in accordance with car position oper- 55 able jointly with said selectively controlled me-

chanical call registering means to cause slow-down in successive steps, followed by a final stop; third, mechanical re-set means to cancel calls initiated from the landings when the first car is intercepted, the arrangement being such as to prevent interception of a second car coming along in the same direction while the first car is responding to a call, which is accomplished by preventing second registration of a call until restart of the car from the landing; fourth, a new and 10 novel drive for the mechanical selectors comprising up and down sets of cams each carried by an arm and the arms of each set are carried by independent shafts driven from the car, the arms being adjustable independently as to those 15 in each set for co-operation with a linear movable actuator at the proper time to compensate for different floor heights and as between the two sets relative adjustment therebetween can be made to allow for different sequential operation necessary for up and down direction of car movement. 20 The linear movable actuator is given only a step-by-step movement rather than a continued movement in accordance with the position of the car and this results in a very considerable reduction 25 in the over-all length of the selector as a unit; fifth, grouping the selectors in a manner to facilitate the use of only a single up and a single down electro-magnet to control the hall registering means common to all cars and with the view of 30 economizing in space taken and size and weight of the mechanical elements. This grouping provides a most practicable way for providing the mechanical connections between the electro- 35 magnets and the common call registering means and also between the call registering means and their associated selectors, because without such grouping which I hold is a very important fea- 40 ture of the invention, economy in the number, size, weight and space taken, could not be obtained and it is by such grouping that a most practicable and economical solution of this me- 45 chanical problem may be attained; sixth, means to control the mechanical selector drive in a manner to initiate slow-down of the car at a given or pre-determined distance from a landing to allow for necessary retarding action for floor- 50 to-floor run with stop at adjacent landings, and which will on the other hand control said selector drive to initiate slow-down at a greater dis- 55 tance from, or far enough in advance of a landing for which a call is registered, to allow for added steps of deceleration necessary for higher car speed as attained when no stops are effected at adjacent landings in which case the greater 55

distance of car movement will enable it to attain such higher speed which is prevented when calls are registered for stop at adjacent landings; 5 seventh; mechanical means whereby each car will in effect re-set only its own car-button calls, the arrangement being such that the re-set operation of the common call registering means of the first car stopped at any particular landing will not disturb any existing calls registered from 10 within the other cars.

Other features will be pointed out hereinafter, the novel combinations of elements and arrangements of parts being pointed out in the appended 15 claims.

15 In the accompanying drawings, Figs. 1, 1A, and 1B, read together illustrate diagrammatically more essential elements of an elevator system having a bank of three cars; Fig. 1 illustrates more particularly the bank of cars etc. together 20 with mechanical selector mechanism and a drive therefor as arranged for each car; Fig. 1A illustrates more particularly and in perspective mechanical call registering means arranged for two intermediate landings for registering up and down stop calls common to all cars of the bank in response to up and down push-buttons located 25 at each of said two landings, also mechanical means for registering calls initiated from the cars, for stop at each of said landings, each call being individual only to its own car and being responsive to push-buttons to be located within 30 each car, there being one push-button within each car for each intermediate landing served, together with mechanical selectors for all three 35 cars of the bank, as arranged for two intermediate landings and for up and down directions of car movement, and combined with certain electrical mechanism to control slow-down mechanism for all three cars and for both directions 40 of car movement; Fig. 1B is a diagrammatic illustration of a car switch multi-speed control system such as is associated with each car and in which the direction for car movement and start is initiated by a car operator followed by automatic acceleration together with automatic decelerating mechanism combined with mechanism 45 to control same and certain other control mechanism arranged in accordance with the present invention to initiate its operation in response to registered calls; Fig. 2 is a somewhat enlarged detail view of mechanical call registering means controllable from the landings and cars by push-button controlled electro-responsive means which 50 initiate operation of said registering means, together with grouped mechanical floor selectors and drives therefor and certain other elements, in accordance with the present invention and as constructed and arranged for an intermediate landing, both directions of car movement and 55 for all three cars of the bank; Fig. 3 illustrates a front elevational view of a portion of the mechanical selector for one floor and one direction of car movement together with certain drive mechanism etc. all as constructed and arranged 60 in accordance with the present invention; Fig. 4 is a side elevational view of Fig. 3; Fig. 5 illustrates a plan view of a certain part of the selector drive illustrated in Figs. 4 and 5; Fig. 6 illustrates somewhat in perspective a portion of certain 65 parts of the drives for three cars and one direction of movement as grouped to drive their associated selectors; Fig. 7 illustrates in perspective and somewhat enlarged the common call registering means whose operation is initiated from an 70 up push-button at an intermediate landing to

register a call common to all three cars of the bank, together with associated floor selectors for all three cars; Fig. 8 illustrates in elevation and as viewed from the side, the common and individual call registering means and their respective selectors as arranged for all three cars, one intermediary landing and for one direction of car movement, and Fig. 9 illustrates in perspective and somewhat schematically the relative positioning of the selectors for all three cars as 10 arranged for three intermediate landings and for one direction of car movement, together with a portion of the drive for the selectors of one car. 15

The system will now be described in detail. In Fig. 2 the elements in general excepting the selector drives and electrical mechanism to control slow-down, are for one intermediate landing only, to initiate automatic slow-down and stop thereat of all three cars of the bank, from said landing and from within each of the cars and 20 for both directions of car movement.

The system may be arranged for any number of landings to be served in which case the elements are duplicated for each intermediate landing served. In providing for each of the end 25 landings certain of the elements are omitted as for example, up call registering means and associated selector mechanism will be omitted for the lower terminal landing, and down call registering means and associated selector mechanism 30 will be omitted for the upper terminal landing.

Since such elements as call registering means and associated selector mechanism are duplicated for each intermediate landing, a detailed 35 description of such elements for one intermediate landing will suffice for all.

At each intermediate landing served there is a single up control means or push-button UHB and a single down control means or push-button 40 DHB effective to register calls common to all three cars of the bank. These call registering means are of the same construction and arrangement and hence a description of one will suffice for all. 45

Operation of the up push-button UHB energizes an electro-magnet which operates a latch 2 to release a bell-crank 3 which now will rock by gravity to register an up call for stop, such call being common to all three cars of the bank. 50

This registration of a call common to all cars of the bank involves establishment of an operative mechanical connection between mechanical selectors S1, S2, S3 for all three cars #1, #2, #3 of the bank respectively and their associated slow-down 55 and stop control mechanism A1, A2 and A3 see Fig. 1A, each of which is controllable in common and for up direction of car movement only, from all landings from the second to the upper terminal, by the provision of only a single up push-button at each landing. The call registering means at a landing by the use of only a single actuating magnet establishes an operative connection between the selectors corresponding to said landing and for all cars of the bank, and the slow-down and stop control mechanism for all three cars, so that in effect, said slow-down 60 and stop control mechanism of the first car to reach a landing for which a call is registered and whose movement corresponds to the call registered will, by reason of the mechanical connection between the selector and the corresponding call registering means, have necessary movement imparted thereto to cause slow-down and stop of the car at the landing. It is obvious that the 70

- car-actuated selector is the source from which said necessary movement is obtained. The call registering means as considered collectively, that is, for a plurality of landings, constitute motion transmitters controlled selectively to establish mechanical connections between, or the coupling together of the selectors of all cars of the bank and their associated slow-down and stop control mechanism.
- These common call registering means each comprises in addition to the bell-crank 3 and rock-shaft 4, see Fig. 7, a rod 5 supported at opposite ends by a pair of links 6 one of which connects with one arm of the bell-crank and the other connecting with a lever 7 keyed or otherwise on the rock-shaft 4, to rock therewith. Motion transmitting levers L₁, L₂, L₃, one for each car for up car movement, see Fig. 7, are each supported at one end and in common on a rod 5 relatively to which they have lost motion movement by being slotted as at 200. Each lever L₁ etc. connects at its other end with its associated lever T₁, T₂ and T₃ respectively, having rocking movement on shaft 8, see Fig. 7. The levers T₁, T₂ and T₃ at their upper ends co-operate with their associated rods R₁, R₂ and R₃ respectively, see Figs. 1A, 2 and 7. Each rod R₁ etc. is independently supported at opposite ends by levers 10 pivotally supported at 11.
- Each rod R₁, R₂ and R₃ has a swinging motion, imparted to it from its associated lever T₁, T₂, T₃ respectively to cause its associated levers 10 to rock and such rocking movement is transmitted from one of these levers 10 associated with each rod and through the intermediary of any suitable mechanical connection such as 12 to associated slow-down control mechanisms A₁, A₂ and A₃ for cars #1, #2 and #3 respectively. Said mechanical connections such as 12 which are for up car travel, and 12' for down car travel are of a construction to impart motion to a commutating mechanism comprising a brush carrier 13 carrying necessary brushes such as 14 and 15, see Fig. 1A, to co-operate with necessary segments such as 16, 17 and 18 for example, to control in successive order energizing circuits for windings 19, 20 and 21 of decelerating relays D₁, D₂ and D₃, which by opening their associated normally closed contacts 22, 23 and 24 respectively thereby open-circuit holding circuits 131, 132 and 133 respectively for the windings 28, 29 and 30 of the activating contacts F, G and H.
- Direction of car movement and start of the cars are controllable only from within each car and a usual car switch CS under control of an operator in each car is provided to control such operations in a well known manner through control of electro-responsive reversing switches RS, RS'.
- A variable speed hoisting motor HM may be controlled as to direction and speed regulation by any well known methods such as are commonly used with variable voltage, multi-speed or rheostat control. As is well known, when variable voltage or Ward Leonard system is used direction of rotation of the hoisting motor and consequently direction of car movement is controlled reversing the direction of current flow through a generator field winding GF of a Ward Leonard system WL.
- The various slow-down contactors such as F, G and H, used in connection with any of the above methods are all well known and form no particular part of the present invention, and they are illustrated merely for the purpose of showing

one way in which the present improved mechanical selective control system and certain electrical elements may be combined therewith to initiate their operation.

It will be observed by reference to Fig. 1A which illustrates certain elements as arranged for two floors and for up and down directions of car movement, that the rod R₁ connecting with the slow-down control mechanism A₁ for car #1, is common to the levers T₁ corresponding to both the second and third landings, and although only two landings are illustrated it will be understood that such rod R₁ is common to all levers T₁ corresponding to all landings from the second to the upper terminal landing; the rod R₂ connecting with slow-down control mechanism A₂ for car #2, is common to all levers T₂ corresponding to the above noted landings, and the rod R₃ connecting with slow-down control mechanism for car #3 is common to all levers T₃ corresponding to said landings above named. The Fig. 1A also shows for each of said landings and for all three cars, the independently movable motion transmitter levers L₁, L₂ and L₃ which connect with the levers T₁, T₂ and T₃ respectively, in association with their respective slow-down mechanisms for both up and down directions of car movement. The selectors S₁, S₂ and S₃ for all three cars #1, #2 and #3 respectively for one landing and up direction of car travel are arranged in one group X, while those for the other direction of car movement are arranged in a second group X' and are designated S₁₁, S₁₂ and S₁₃ and their associated motion transmission levers are designated L₁₁, L₁₂ and L₁₃.

The selector for each intermediate landing, for each car and for each direction of car movement, see Fig. 3, consists of a segmental gear 32 which together with those for all the other landings may be freely supported for rocking movement on a common shaft 33. Each segmental gear has imparted to it from its associated drive which for cars #1, #2 and #3 are designated, D₁, D₂ and D₃ respectively, a limited rocking movement which is transmitted by an arm 34 to its associated arm 35 to move same transversely to the longitudinal axis of its associated toothed driving spindle which for the three cars are designated DS₁, DS₂ and DS₃, respectively, see Fig. 1. Said driving spindle such as DS₁ for any one car is aligned with all its associated selectors corresponding to one direction of car movement, and its over-all length is in some proportion to the over-all distance of car travel.

The selectors of each group and for each landing are arranged side-by-side relatively close to each other as viewed in Fig. 1, but slightly off-set as viewed from the side as in Figs. 8 and 9, so that their associated arms 35 move transversely in different planes.

Such grouping and arrangement of the selectors is a very important feature of the present invention since it provides a most practical way for mechanically connecting selectors for all cars of the bank with the common call registering means as provided herein to be actuated by a single electro-magnet. By such grouping, the levers 35 are relatively short in length which means a consequent saving in weight and space, whereas if the selectors were not so purposely grouped but were widely separated and arranged relatively close to their associated hoisting mechanism as is usual with the electrical type of selector now used in conjunction with "signal control", such economy in length, weight and space

could not be obtainable particularly if the very economical and simple construction for registering a call common to all the cars of the bank by the use of only a single electro-magnet is adhered to. Indeed it may be that without so grouping the parts, the results as obtained herein by mechanism essentially mechanical would be difficult of attainment without being prohibitive as to cost, use of space, size and weight of the elements which in order to be practical should be kept within reasonable bounds.

Each lever L₁, L₂ and L₃, L₁₁, L₁₂ and L₁₃ in both the up and down groups X and X' respectively, for each intermediate landing has a tooth 36, and carries at its end a pivotally supported lever having a tooth 38. These levers for car #1 and in the up group are designated C₁U-2 and C₁U-3, see Fig. 1A, while those for car #1 and in the down group are designated C₁D-2 and 15 C₁D-3. Said levers for car #2 and in the up group are designated C₂U-2 and C₂U-3, and in the down group C₂D-2 and C₂D-3. Said levers for car #3, and in the down group are designated 20 C₃D-2 and C₃D-3, and in the up group, C₃U-2 and C₃U-3. It will be obvious that in the above 25 designations the numeral first appearing identifies the car with which the lever is associated and the numeral last appearing identifies the particular landing with which the lever is associated.

The teeth 36 and 38 are off-set from each other as viewed from the side as in Fig. 8 and each of the selector levers 35 is likewise provided with two teeth 36' and 38' off-set relatively to each 30 other to co-operate with the teeth of the levers L₁, L₂ etc., such co-operation of course being between the two sets of teeth which correspond as to the car, landing and direction. Said teeth 36' and 38' are arranged on opposite faces of their 35 associated levers and are pivotally supported to enable them to rock freely in one direction but not in the other.

The levers C₁U-2, C₂U-2 etc., are in effect 40 mechanical selectively operable call registering means controlled only from their associated cars from which point their actuation to register calls is initiated and such initiation is controlled by means of the push-buttons located within each car, one for each landing served.

In Fig. 1A, car buttons for cars #1, 2 and 3, and for the second and third landings are designated as follows; for the second landing, within 45 car #1, CB₁-2; within car #2, CB₂-2; within car #3, CB₃-2. For the third landing, within car #1, CB₁-3; within car #2, CB₂-3; within 50 car #3, CB₃-3. Fig. 1 also illustrates up and down hall buttons UHB and DHB to be located at the second and third landings.

Associated with each lever such as C₁U-2 etc. 55 is a releasable latch 39 which normally keeps its lever in its raised or what may be termed a non-call-registering position as will be observed from Figs. 1A and 2. Calls registered from any particular car are individual to that car only, that is to say, they will initiate slow-down and cause 60 final stop, only of their own car, and this function of the car buttons is to be distinguished from that of the hall buttons which as mentioned heretofore register calls common to all three cars of the bank to cause stop of the first car.

This individual registration is effective because 65 each of the call registering means such as C₁U-2 etc., for any particular car, is responsive to, or set in registering position only in response to the 70 car button with which such elements are associ-

ated. Furthermore each car button registers such an individual call only for its own car by releasing the levers in both the up and down groups, which correspond to the particular car from which the call is initiated. This result is 5 accomplished by providing in association with each latch 39 in both groups a trip device 40. Thus, for each landing and for each car there is provided a pair of trip devices one in the up group and one in the down group and each pair 10 of trip devices is actuated through a mechanical link connection 41, by an electro-magnet 42, and energization of each is controlled only by the push-button within the particular car which corresponds thereto.

Momentary pressure of the second landing car button CB₁-2 corresponding to car #1 energizes its corresponding electro-magnet 42 and the latter is made self-holding by the provision of a self-holding circuit 43 controlled by holding contacts 44. Energization of said electro-magnet 42 causes the latter to actuate the pair of trip devices 40 carried by levers L₁, L₁₁ in both the up and down groups, such levers corresponding with car #1 and to the second landing. Said 20 trips 40 co-operate with the latches 39 to cause release of the pair of levers C₁U-2 and C₁D-2 in both the up and down groups. These levers being unlatched will drop by gravity to bring their teeth 38 into alignment with the teeth 38' 30 of the selector S₁ and S₁₁ for car #1 and for the second landing. Such operation of the levers C₁U-2 and C₁D-2 by dropping their teeth into alignment with their associated selector teeth is in effect a call registering operation because it 35 establishes an operative connection between the slow-down control mechanisms A₁ and A₁₁ for car #1 and the selectors S₁ or S₁₁ of the up or down group depending on the direction of car movement so that motion imparted to 40 one or the other of said selectors will in turn be transmitted to said slow-down mechanism through the intermediary of said connection as effected by the registering means and its connecting parts. Thus it will be seen that operation of the second landing car button for car #1, initiates registration of a call for stop only for car #1 at the second landing. It will be seen that pressing a button, in effect causes what may be termed a manual coupling of one part of the 45 actuating mechanism for the slow-down control mechanism with the other part of said actuating mechanism operable in accordance with car position.

Consider now the operation of the hall push-button UHB-2 located at the second landing. Momentary operation thereof causes energization of the magnet 1 which by being energized actuates the latch 2 to unlatch the bell-crank 3 and by so doing registers a call for up stop at the second landing, common to all cars. Unlatching the bell-crank permits it to drop by gravity carrying with it the transmitter lever L₁, L₂ and L₃ of all three cars of the bank. Dropping these levers, 50 brings their associated teeth 36 into alignment with the teeth 36' of their associated selectors corresponding to the second landing. By so bringing said teeth into alignment there is a mechanical coupling together of, or mechanical connection established, between the slowdown 55 control mechanisms A₁, A₂ and A₃ and their associated selectors which correspond to the second landing, so that the first car of the bank to approach within a pre-determined distance of the second landing and which is traveling in an as- 60

5 cending direction, will by imparting motion to its corresponding selector for such landing cause such selector to impart motion by way of such coupled parts to its associated slow-down control mechanism to impart thereto degree of movement necessary to decelerate the car, and final stop may be effected in any well known manner either by leveling or non-leveling switch mechanism on the car and co-operating cams 10 therefor in the hoistway or their equivalents.

10 The manner in which the down slow-down control mechanisms A₁₁, A₁₂ and A₁₃ will operate in response to registered calls is thought to be obvious in view of the detailed description already set forth for ascending car movement.

15 A detailed description of the new and novel selector drive will now be given and for such purpose reference will be made more particularly to Figs. 1 and 2 to 6 inclusive.

20 The selector drives are the same for all cars and a description of such drive in association with one of the cars will suffice for all. Take the drive for the selector mechanism S₁, for car #1, the up group. It comprises what may be termed 25 an immediate drive designated as a whole D₁. Each immediate drive comprises the toothed spindle DS₁ rotatable in accordance with movement of the car at a rate which is much slower and in some proportion to car speed. A pinion

30 S₁ is in constant mesh with said spindle. The pinion S₁ is carried by a suitable carrier or traveler 52 guided for longitudinal movement by a suitable pair of guides such for example as are illustrated conventionally at 53.

35 The traveler 52, pinion etc., may as a unit and for convenience of description be termed a reciprocator and as a unit will be designated R. The reciprocator R, see Fig. 4, is given a step-by-step movement to the right or left as viewed 40 in Fig. 4, depending on direction of car movement, and in a plane parallel with the axis of the toothed spindle DS₁ and in accordance with car position by a series of rotatable slotted cams such as 54, one for each landing served, said cams being carried by respective arms 55 carried by a rotatable shaft 56, said cams being adjustable relatively to each other on said shaft by the provision of adjusting nuts 58, such adjustability being necessary to allow for varying floor heights.

45 There being two sets of these cams one for up and one for down direction permits relative adjustment on their independent shafts, and as between the two sets to allow for different sequential operation for up and down car movements. The 50 shaft 56 is rotated at a relatively slow rate in accordance with movement of the car by a connection described hereinafter, to rotate said cams so that the slot 57 in each, will, when the car is a pre-determined distance from a landing cor-

55 responding to any given cam, engage a roller 58 on the under side of the reciprocator to impart to the latter a short but relatively quick movement to move the pinion S₁ out of mesh with the segmental gear of a selector corresponding to the landing which the car is moving away from and into mesh with the segmental gear of the selector corresponding to the next or adjacent landing above. During such shifting movement of the pinion S₁ it remains in mesh with and

60 slides along the toothed spindle and consequently being rotated during said shifting movement. Since the pinion S₁ rotates at the time it is brought in mesh with the segmental gear, it may be desirable in practice to provide the pinion S₁ and also the segmental gear with chamfered

teeth to facilitate easy mesh and both of these gears may be of any well known noiseless composition, but it may be that due to their relatively slow rate at which the pinion S₁ rotates, such noiseless construction need not be resorted to. The adjustment of the up cams may be made so that when the car is ascending such step-by-step movement or impulse of the reciprocator is effective to throw the pinion S₁ into mesh with the segmental gears of the landing being ap-

10

10 proached, say for example when the car is at a distance from said landing which is a little less than the floor height between the two adjacent landings and in this way motion is imparted to the segmental gear of such landing being ap-

15

15 proached, to rock same in a clockwise direction and such rocking movement of the selector, if a call is registered from the landing or from the car, is transmitted to the slow-down mechanism for the associated car. Hence it will be seen 20 that the selector will impart movement to the connection 12 which is of a pre-determined range corresponding to a floor-to-floor movement of the car, and by adjustment of the fixed segments relatively to the traveling brush and to each 25 other, the decelerating and stop operations can be rendered effective at the necessary points within the over-all range of movement of the brush-carrier.

20 From the description thus far given it will be seen that the rotatable slotted members 54 by imparting a step-by-step movement to the reciprocator R connects the selectors for the various floors successively with the source of mechanical power, which results in actuation of the 30 arms 52 successively and transversely to the longitudinal axis of the toothed spindle DS₁. Hence it will be obvious that the car-actuated mechanical selectors operating jointly with the selectively controlled mechanical call registering 35 means cause actuation of the slow-down control mechanism to initiate operation of the decelerating contactors in a manner to cause slow-down and stops successively or in the natural order of landings, regardless of the order in which said 40 calls are registered.

45 Means are provided herein which act as a tell-tale for car speed or motor speed, the tell-tale employing the latter being illustrated herein, but car actuated governor controlled contacts (not 50 shown) may be as effectively used. I employ a C. E. M. F. (counter-electro-motive-force) relay having three sets of top contacts, 130 to 132 inclusive and back contacts 133, and whose winding is connected across the armature of the hoist- 55 motor to act as a tell-tale for speed of the latter and consequently of the car.

The contacts 130 are included in a circuit including contacts 134 of a relay 135 responsive to higher speed contacts 62 of the car switch CS, 60 and winding 28 of the higher speed accelerating relay F, said circuit being traced as follows; from a plus wire 136, contacts 134 which are closed by energization of a winding 135 from the higher speed car switch contact 62, wire 137, contacts 65 130 of the C. E. M. F. relay so designated, wire 138, winding 28 of the higher speed accelerating relay F, and thence to the minus line by way of wire 139. With this arrangement, even though the car operator may at start throw the car switch to 70 full "on" position onto the higher speed contact 62, the higher speed relay F cannot become effective to cause higher car speed until the speed of the motor is sufficient to cause operation of the C. E. M. F. relay.

The car travels a pre-determined distance before attaining a speed necessary to cause operation of the C. E. M. F. relay and according to the construction of the mechanical selector etc., the 5 pinion 51 is shifted out of mesh with the segmental gear corresponding to a landing which the car is starting say the second for example, and into mesh with the segmental gear corresponding to the third landing, such shifting being effected 10 when the car has moved a short distance from the second landing. Such meshing results in actuation of the third landing lever 35 and if a hall call is registered from the third landing before the tooth 36' clears the tooth 36 of each of the 15 common registering means which results in coupling together of said common registering means and the selector, such movement of the selector 35 by a first car, say car #1 for example is imparted to the slow-down control mechanism A1 20 for said car before the latter has moved the pre-determined distance calculated as necessary to cause operation of the C. E. M. F. relay and consequently before higher speed operation is effective by operation of the higher speed accelerating 25 relay F. Such actuation of the slow-down mechanism A1 results in deceleration of car #1 through the control of the two lower speed relays G and H followed by final stop controlled by the stop switch SS.

30 Each slow-down control mechanism such as A1 for example, has associated therewith two movable brushes 14 and 15 carried by a brush carrier 13. The brush 15 co-operates with the fixed but adjustable segments 17 and 18 to engage same successively to control decelerating relays D2 and D3 for slower car speed and for floor-to-floor runs with stops at adjacent floors, in which case the range of movement of the brush carrier 13 for such runs is less than that for more than a one floor run, in which latter case the car will travel a distance enabling it to attain a speed sufficiently high to cause operation of the C. E. M. F. relay.

In order properly to decelerate from the higher speed, the higher speed relay F is brought under control of the slow-down mechanism such as A1 45 for example, by associating therewith a fixed segment 16 and movable brush 14. When the C. E. M. F. relay operates, it opens its back-contacts 133 to render the floor-to-floor brush 15 ineffective and closes its top contacts 131 to render the rear brush 14 effective. Contacts 131 complete a circuit as follows; from a plus wire 149, contacts 131, wire 64 to a junction 250, parallel wires 251 and 252 connecting with rear brushes 14 and 14' of the up and down slow-down mechanisms A1 and A11 respectively.

The brush 14 is adapted successively to engage the brushes 16, 17 and 18 and to do so requires a longer range of movement of the brush carrier 13 than is required for the floor-to-floor run. Furthermore, because of the higher car speed it is necessary to initiate slow-down sufficiently in advance of the landing to be stopped at in order to obtain proper deceleration.

Hence in accordance with the present invention there is provided what will be termed an advance pinion 66, see Figs. 4 and 9 carried by the reciprocator adjacent to and in advance of, that is, with respect to its working movement, the pinion 51 and in constant mesh with the toothed spindle DS1. Normally said pinion 66 lies in a plane sufficiently below that of the pinion 51 so that it will not mesh with the segmental gears of its associated selector. When the motor speed 70 has increased sufficiently to operate the C. E. M. F.

relay, the latter closes contacts 132 to energize 67 which through a toggle connection 68 with a depressible shaft 69 carrying the pinion 51, lowers said shaft and in this manner the pinion 51 is lowered to a non-meshing plane with respect to the selector segmental gear teeth. 5

The shaft 69 co-operates with a slot 70 in the reciprocator standard and is guided thereby to retain said pinion 51 in mesh with the toothed member DS1 during its movements to lowered and raised positions. An additional magnet 71, energized simultaneously with the magnet 67, actuates the advance pinion 66 through the intermediary of a toggle connection 68 similar to that of the pinion 51, from its normally lowered to a 15 raised position.

The circuit for the magnets 67 and 71 in parallel may be traced as follows;—from a plus wire 148, contacts 132, wire 141, normally closed contacts 142, of a relay 143 having a winding 144 controlled by a movable brush 145 controlled by slow-down mechanism A1, wire 147, contacts 148 of a relay 159 controlled by an up relay RU, wire 149 to a junction 150 wherefrom parallel wire 151 and 152 extend to the windings 67 and 71 respectively, the wire 152 including normally closed contacts 153 of a relay 164 controlled by the down directional relay RD, thence through said windings to the minus line by way of wire 155. 20 25

Continuing now with the operation, such advance gear now being elevated and in mesh results in initiating movement of the brush carrier 13 substantially two floors in advance of the car and the brush carrier as a result of its actuation in a continuous manner first by the pinion 66 and then by the rear pinion 51 will have imparted to it a longer range of movement to cause the rear brush 14 successively to engage all three segments 16, 17 and 18 thereby to control all decelerating steps through control of all decelerating relays D1, D2 and D3 successively in the order named. 30 35 40

It will be obvious that in making a two floor run, the reciprocator pinions 66 and 51 will be given two impulses, or in other words shifted twice in a linear direction, say for example, one after the car leaves the second landing and which impulse brings the advance pinion 66 into a position to mesh with the fourth landing selector segmental gear, and a second impulse after the car passes the third landing thus bringing the advance gear into alignment with the fifth landing segmental gear and the rear pinion 51 is now in alignment with the fourth landing segmental gear. 45 50 55

If a call is registered at the fourth landing sufficiently in advance of actuation of its associated selector arm 35 by the advance pinion 66, the brush carrier 13 will have been moved a pre-determined distance by the time the car reaches the third landing thus to cause the travelling brush 14 to pass over the segment 16 to cause the first slow-down operation by effecting operation of the higher speed decelerating relay D1, and such movement of the brush carrier causes a brush 145 to pass over a fixed segment 146 to energize the winding 144 of relay 143 and the latter operates to open the normally closed contacts 142 included in the common feed 141 heretofore traced for the magnets 67 and 71 thus to de-energize the latter to permit the advance pinion 66 to move to a lower plane or inoperative position and the rear pinion to be elevated to its operative plane such operation being timed to be effective simultaneously with the second shift of the recipro- 60 65 70 75 75

cator which with the rear pinion now elevated, brings said elevated pinion 51 into mesh with the fourth landing segmental gear and the latter continues movement of the brush carrier 13.

5 Such lowering of the advance gear 66 simultaneously with the second shift of the reciprocator is necessary under the circumstances, to prevent it meshing with the fifth landing segmental gear, since a stop is to be made at the 10 fourth landing.

Hence for the two floor run the advance gear 66 meshes with the segmental gear corresponding to a landing substantially two floors in advance of the car and will in response to a call 15

impart necessary movement to the brush carrier to cause operation of the higher speed decelerating relay D1 to initiate the first slow-down operation from higher speed, and then the advance gear is thrown out of mesh substantially 20 at the time when the reciprocator is shifted and the rear pinion 51 is elevated into mesh with the selector corresponding to the landing to be stopped at and hence said pinion 51 continues the movement of the brush carrier to cause operation of the two final decelerating relays D2 25 and D3, said rear pinion and the selector segment remaining in mesh with the car stopped at the landing.

It will be particularly mentioned at this point 30 that the C. E. M. F. relay is of a particularly novel construction which in detail is illustrated in Fig. 1B. The armature 76 may be arranged with an air gap 77 adjusted by adjusting screw 78, and in this way the C. E. M. F. winding 157 35 can be made to operate its armature at the desired speed of the hoisting motor and such operation bears some relation to the distance which the car has moved and can be calculated.

The armature 76 when in its attracted position 40 is maintained in such position by a self-acting latch 78. The latch 78 is normally held in a raised position by a spring 79 and is rocked on a pivot 80 by an electro-magnet 158 whose energization from the plus wire 160 and wire 161 45 is conditional on starting the car as for example is accomplished by including in its circuit normally open contacts 81 and 82 in parallel of the up and down starting relays RU and RD respectively. With such an arrangement the 50 operation of the contacts associated with the C. E. M. F. relay from normal position is related to speed of the hoisting motor, but the return of said contacts to normal position is independent of speed and is conditional on the final stopping operation of the car as for example by de-energizing the up and down relays RU and RD 55 which opens said contacts 81 or 82 to de-energize the winding 158 to permit the spring 79 to actuate the latch 78 to release the armature 76. By 60 making return of said contacts particularly those designated 131 which control the feed for the brushes 14 and 15 or 14' and 15' conditional on final stop, thus gives assurance that the feeds 251 or 252 to said brushes 14 and 14' will be maintained closed and the feed 65 for brushes 15 and 15' will at the same time remain open, which operations are necessary in order that the decelerating relays may not possibly operate out 65 of proper sequence which might happen if the C. E. M. F. relay without the latch or its equivalent is relied upon to release the armature and this is so because time at which it will release is uncertain, it being understood that the closed 70 armature or sealed armature will let go at a

speed considerably lower than that required to attract the armature from normal position with an open air-gap.

Furthermore the engagement of the brush 145 5 with segment 146 bears direct relation to position of the car which insures de-energization of the windings 67 and 71 in proper sequence with respect to shifting of the pinions from one segmental gear to the next during deceleration but such proper sequence of operation could not be 10 relied upon if the de-energization of said windings were dependent on the opening of the C. E. M. F. contacts 132.

Friction devices FD, FD' are operated through frictional connection with members 12, 12' respectively, to actuate their associated contacts 680, 680' respectively to open-circuit same thus to open-circuit the feed circuits 65 to the brushes 15, 15' when the members 12, 12' are returned 15 from their actuated positions to their normal 20 positions as shown, thus to prevent possible false operation of the decelerating contactors during such return movement of said members 12, 12'.

At this point it will be mentioned that the 25 windings 81 and 82 of the reversing switches which control the generator field winding to control direction of car movement are controlled by up and down directional relays RU and RD respectively having windings 83 and 84 respectively controlled by the car switch contacts 85 30 and 86, switch segment 87, and a feed contact 162 connecting with a plus feed wire 163.

The car operator in order to control start and acceleration needs only to move the car switch in the direction corresponding to the desired direction of car movement and to full on position momentarily and can then return it to its normal position in which case the running of the car and acceleration is automatic and requires no further attention of the operator. 35

This automatic operation is well known and therefore needs no detailed description and is effected by providing self-holding circuits 88 and 89 respectively for the windings of the relays RU and RD, and self-holding circuits 25 and 26 40 45 for the windings 39 and 29 of the first and second accelerating relays H and G respectively. The higher speed contact 92 of the car switch controls an energizing circuit for the winding 92 of the relay 135 and said relay is made self-holding by 50 a circuit 94 controlled by the contacts 95 and 96 of the up and down relays RU and RD. The relay 135 is provided with contacts 134 in series with the C. E. M. F. contacts 130 to control energization of the winding 28 of the higher speed 55 accelerating relay F.

By making the relay 135 self-holding, the car switch need not be held in on position until the C. E. M. F. operates in response to speed in order to effect operation of the higher speed relay F 60 since the contacts 134 are held closed independently of the car switch to close the energizing circuit for winding 28 at one point and the closure of said circuit at the second by the C. E. M. F. contacts 130 completes said circuit to cause 65 operation of the accelerating relay F.

The initial energizing circuit for the winding 92 may be traced as follows;—from plus wire 163, through car switch by way of contact 162, segment 87 and contact 62 to wire 164, through winding 92, wire 165, normally closed contacts 22 of the higher speed decelerator relay D1, and to the minus line by way of wire 166. A holding circuit for said winding 92 is as follows;—from the plus 70 75

wire 160, contacts 95 or 96 in parallel to feed a wire 94, holding contacts 163, wire 160 which forms a junction at 170 with the initial energizing wire 164.

5 From what is said above, it will be seen that the circuit for the winding 28 is controlled by the C. E. M. F. contacts 130, and the contacts 134 in series. Contacts 130 remain closed until stop of the car but contacts 134 are open-circuited to 10 de-energize the winding 28, by operation of the slow-down mechanism A! to bring the brush 14 into engagement with the segment 16 thus to complete an energizing circuit for the winding 19 of the decelerating relay D1 causing operation 15 of the latter to open its contacts 22 to open the holding circuit for the winding 92 of the relay 135 thus permitting the latter to open its contacts and in such manner de-energize the winding 28 of the high speed relay and by so doing 20 cause the latter to open its associated contacts 170 to cause the first slow-down from the higher speed operation of the car.

To effect final stop of the car usual well known leveling mechanism (not shown), may be used 25 such mechanism having a directional function, but if desired a non-directional normally closed stop switch SS on the car may be provided it having a roller 99 to co-operate with up and down stop cams 100 and 101 located in the hoist-way at each intermediate landing served and for 30 each end landing there is only one of these cams.

This switch is provided with an electro-magnet 162 having a circuit 163 controlled by contacts 164 of the first accelerating contactor H.

35 The electro-magnet 162 when energized actuates the stop switch and roller to a retractive position said switch at the same time maintaining its contacts closed, to prevent the roller from striking cams at the landings not stopped at. 40 However when the contactor H operates to cause the final decelerating step its contacts open the circuit 163 to energize the retractive winding thus to permit the stop switch to assume a position so that its roller will be in a cam engaging 45 position. When the car reaches the stopping distance from the landing, the roller engages one or the other of the cams thereby causing opening of the stop switch contacts which open the self-holding circuit 88 or 89 of whichever directional relay is closed and such relay opens its associated contacts 105 or 106 to open their associated circuits for the reversing switch windings 81 or 82 respectively and a reversing switch opens thus to open the circuit of the generator field 50 winding and in such manner cause final automatic stop of the car.

55 Referring now more particularly to Fig. 1. In the over-head or basement there is in association with each car a shaft 107 driven from the car by any of the usual types of drives as for example a cable and drum, sprocket and chain or tape and reel, the latter type being illustrated herein and comprises a pair of tapes 108 and their reels are designated 309. There may be a mechanical connection between the shaft 107 driven by the reels and the shaft 56 of the immediate selector drive.

60 However grouping the selectors as has been done herein and also their immediate drives D1, D2, etc., means that certain of said selectors with their immediate drives may be some distance remote from their associated machines. While it is possible and practicable to provide suitable mechanical connections from the driven shaft such 65 as 107 for each car to its associated immediate

selector drive, it may be preferable to drive such remotely located immediate drives from their associated driven shafts 107 by a system well known and identified as the Selsyn system in which the driving motor 108 is connected through 5 suitable reduction gearing 250 with the shaft 107, and the driven motor 108' electrically connected by cable connections contained within a conduit 109, with the driving motor 108, is mechanically connected by suitable sets of gearing 10 such as 116 for example with said shaft 56 and by such arrangement car movement is accurately reproduced and transmitted to the rotatable shaft 56 which as will be remembered carries the 15 rotatable cams 54.

20 Of course it will be understood that each of the three cars of the bank is provided with this Selsyn motor method of reproducing movement of the car and transmitting it to the associated shaft 56.

25 The toothed spindle DS1 associated with each car and for the up group may be driven in accordance with movement of its associated car by suitably connecting its shaft 112 with its associated shaft 56 as for example by a sprocket and 25 chain connection 111.

30 The selectors in the down group for each of the three cars of the bank are driven from each of their associated shafts 56', by the same type of mechanism as used and already described for the up group, it being understood of course that the advanced and rear pinions are in reversed relation as between those in the two groups.

35 Shafts 56' for such down group are each mechanically connected with and driven from the shafts 116 intermediate their associated shafts 56 and driven Selsyn motors corresponding therewith in the up group by any suitable means such as sprocket and chain connections which for car #1 is designated 113; for car #2, 114; for car 40 #3, 115.

45 Referring now to another feature of the invention. When any car is ascending its associated reciprocator pinions 51 and 66 of the up group are operative to actuate the selectors associated therewith in the up group but the reciprocator pinions 51' and 66' are inoperative to actuate the selectors associated therewith in the down group. The advance pinions 66 and 66' in both the up and down group for any car are in a normally 50 lowered plane or non-meshing plane with respect to the teeth of the segmental gears. Now, when any car is ascending its associated pinion 66' in the down group is caused to remain in such inoperative plane by including in the circuit for 55 its associated magnet 71', the normally open contacts 116 of a down relay 764 controlled by the down relay which in effect means that said magnet is effective to be energized by closure of the C. E. M. F. contacts 132 only when the car is 60 descending. In this way the down advance pinion is prevented from being elevated in response to closure of said C. E. M. F. contacts 132, into a meshing plane when the car is ascending. The rear pinion associated with said advance is at 65 this time also lowered to a non-meshing position by its magnet 67' whose circuit 175 is now energized from the contacts 117 closed when the car is ascending by energization of their associated winding 176 by way of contacts 177 and 70 circuit 178 controlled by the up directional relay RU.

75 From what is said above, it will be obvious that for any ascending car, the selector corresponding thereto in the down group will not be operative,

that is, will not have motion imparted thereto because both the advance and rear pinions 66' and 55' are in a lowered or non-meshing plane.

A similar arrangement is provided to so lower 5 both pinions in the up group for any car when it is descending.

The reciprocators R and R' in the up and down groups respectively for any car will be advanced in one direction or the other according to direction of car movement and their position therefore always bears correct relation with the car's position and furthermore the independent adjustment of the two sets of cams on their independent shafts results in such advance movements of the up and down reciprocators being effective in different sequences for up and down car travel, while those in each set are adjustable relatively to each other to allow for varying floor heights.

Reference will now be made to Figs. 2 and 7 20 for a description of the mechanical re-set operation of the elements responsive to a hall-button which registers a call common to all cars and those responsive to a car button to register the call individual to its own car. Automatic re-set 25 of the common call registering means consists of a cam 110 on each of the selector levers 35, effective during its working movement, and shortly after initiation of such movement, and by co-action with a fixed roller 411 to elevate its lever 30 and this movement is transmitted to the rod 5 which supports all the levers L1, L2, etc., for the three cars, in common, and in turn to the link 6 and lever 3 to rock the latter to a re-set position as shown in Fig. 2, and the trip 2 drops by gravity 35 into the position shown to retain the lever 3 and connected parts in re-set position.

In this manner the first car of a bank which actuates its selector arm 35 effects a mechanical and automatic re-set of all the levers L1, L2 and L3 40 corresponding to all cars of the bank and such re-set is effective practically as soon as slowdown is initiated so that a second car coming along in the same direction and close to the first car will not receive the call because the tooth 36 of its associated selector will be in non-cooperative position with respect to its associated tooth 36' so that the latter will merely move freely past, or clear the tooth 36, and in such manner only the one and first car will be intercepted. When the lever 3 is so returned to its 45 re-set position a latch 113 releasable by a latch 114 actuated in common by the lever such as T1 for all three cars and through the intermediary of associated rods 115 abutting said latch, engages a pin 117 on the latch 3 and maintains such call registering means in the re-set position and so prevents registration of a second call until the first car re-starts from the landing, at which time such arm as T1 corresponding to said first 50 car is permitted to return to its normal position as shown through the action of a weight, spring or equivalent means, a spring 118 being shown. Such return movement is effective when the pinion 51 is shifted as when the car is a short 55 distance from the landing stopped at and such shifting can be effective when desired by adjustment of the slotted cams which actuate the reciprocator. Such shift also permits return movement of the selector arm 35 to normal position by the action of a spring 119 or other equivalent means.

It will be obvious that the tooth 36', when the lever 35 is elevated during working movement, is maintained in engagement with the tooth 36 60 when the associated lever is elevated to re-set

position and this is so because the lever 35 remains cammed in its elevated position subsequently to the re-set operation and does not return to normal position until restart.

If the hall or common call registering means 5 are in non-call-registering position as shown, the individual car call registering means such as CIU-2 etc. rock in a clockwise direction in response to car button calls to align their associated teeth 38 with the teeth 38'. Such levers 10 in both groups are re-set collectively as the car nears the terminal landings.

Re-set of the common call registering levers L1, L2 and L3 by a first car does not disturb or cause re-set of calls registered from other cars 15 since each call registered from a car is maintained until its associated lever such as L1 etc. by its working movement, carries the trip latch 39 out of co-operative relation with its associated latch 40. 20

It will be remembered that the relays responsive to car buttons are self-holding which means on the one hand that each operated relay retains its associated latch 39 in released position and it will be obvious then that the re-set or raising 25 of the levers L1, L2 and L3 for all three cars will not disturb the action of the trips 40 corresponding to the other two cars in maintaining their associated latches 39 released from their 30 associated levers CIU-2 etc.

In this manner the individual car button calls registered for such other two cars of the bank will remain registered while at the same time the common call registering means are re-set by the first. This in effect means that a call registered 35 from any particular car for stop, will regardless of whether a common call is registered from the corresponding landing, remain registered and will be re-set at the terminal landings, while on the other hand, the common call registering means 40 will intercept the first car of the bank whose direction of movement corresponds thereto and such first car will mechanically re-set said common call 45 registering means.

The magnets 42 responsive to the car-buttons 45 are self-holding, and a holding circuit may be traced (see Fig. 1A) from a plus wire 265, holding contacts 266, winding 42, wire 267 and thence through two sets of normally closed contacts 268 and 269 of down and up re-set switches 270 50 and 271 respectively. These reset switches are what may be termed a magnetic type with their pivotally supported windings 272 and 273 and cores as a unit being located on the car and their magnetizable armatures 274 and 275 respectively 55 being located near the lower and upper limits of car travel. Said windings on the car are off-set from each other and their associated armatures in the hoistway are similarly arranged.

The windings 272 and 273 are energized one 60 at a time in accordance with direction of car movement, the former being energized by closure of contacts 276 controlled by a down directional relay 277, and the latter being energized by closure of contacts 278 controlled by an up directional relay 279. The windings 280 and 281 65 of said relays may obviously be connected in parallel with the windings 84 and 83 respectively of relays RD and RU, as by wires 501 and 500 respectively. 70

All of the car button controlled magnets for each car are provided with a self-holding circuit and all of such circuits for each car are subject to their associated two sets of contacts 268 and 269 in series. 75

With this arrangement when a car ascending, its re-set winding 273 is energized but without effect on the contacts 269 until the car nears the upper terminal landing at which time the winding 5 and fixed armature in the hoist way are brought into attractive relation thus causing the winding together with the core to rock and in this manner the contacts 269 are open-circuited to open the self-holding circuits subject thereto for the magnets 42, and the armatures of the latter will return to re-set position carrying with them the trips in both groups.

For descending direction of car movement, the 15 down re-set magnetic device will operate in a similar manner to re-set the trips 40 in both groups when the car nears the lower terminal landing to bring the magnetic device 270 into magnetic relation with the fixed armature or magnetizable member 274.

20 When the car is ascending and the re-set switch 271 operates, it closes contacts 381 momentarily to energize the electro-magnet 380 and 283 in parallel, with the result that both sets of fingers 284 and 378 operate to re-set both sets 25 of call registering levers C1U—2, C1D—2 etc.

When the car is descending and the device 270 operates, it closes contacts 282 momentarily to energize the electro-magnets 380 and 283 in parallel, with the result that both sets of fingers 30 284 and 378 operate to re-set both sets of call registering levers C1U—2, C1D—2 etc.

It may be preferable to omit the self-holding 35 circuits for the car button relays in which case the relays operate the trips 40 only momentarily to register a call, and the registering levers corresponding to direction of car movement will be 40 mechanically re-set by the camming action of the lever 35 during its working movement, which action will rock a registering lever to non-registering or re-set position to be retained by its associated latch 39, and the registering levers in the group which do not correspond to direction of car movement will be re-set collectively at the 45 terminal landings by one or the other sets of registering fingers 284 or 378.

Having thus described the invention what I claim is new and desire to protect by Letters Patent of the United States is:

1. In combination, an elevator car, and a control system therefor comprising a plurality of control switches, one at each of a plurality of landings mechanical motion transmitting means controlled selectively by said control switches to register calls to cause slow-down of the car at landings for which calls are registered, and means 50 operable manually only from within said car to cause start thereof.

2. In combination, a plurality of cars operating in a bank, and a control system therefor comprising a control switch at a landing mechanical motion transmitting means controlled by said control switch to register a call common to all cars of the bank, to cause slow-down of the first car to reach a predetermined distance from the landing 60 for which said call is registered.

3. In combination, a plurality of elevator cars operating in a bank, a single up and a single down control switch at each of a plurality of landings, mechanical motion transmitting means responsive to its corresponding up control switch to register a call common to all cars of the bank, and mechanical motion transmitting means responsive to its corresponding down control switch to register a call common to all cars of the bank.

4. In combination, a plurality of elevator cars

operating in a bank, a single up and a single down control switch at each of a plurality of landings, a plurality of control switches within each car one for each of said landings, mechanical motion transmitting means responsive to said up and down control switches to register calls common to all the cars of the bank, and mechanical motion transmitting means responsive to said control switches within each car to register calls for stop, said calls being individual to 10 the car from which they are initiated.

5. In combination, an elevator car, a plurality of control switches one at each of a plurality of landings mechanical call registering means comprising for each of a plurality of landings a motion transmitting member responsive to said control switches and operable jointly with car actuated mechanical selector mechanism to cause automatic slow-down of the car at landings for which calls are registered, and means only within 15 the car to control its starts.

6. In combination, an elevator car, a control switch at each of a plurality of landings, mechanical selector mechanism actuated in accordance with car position, mechanical call registering 25 means comprising a plurality of motion transmitting members controlled by said control switches to be coupled with said selector mechanism for actuation thereby to cause slow-down at landings for which calls are registered, and 30 means only within the car to control its starts.

7. In combination, a plurality of elevator cars operating in a bank, mechanical selector mechanism for each car actuated in accordance with car position, a single up and a single down control switch at each of a plurality of landings, and mechanical call registering means to register up and down stop calls common to all the cars of the bank in response to said single up and a single down control switch at each of a plurality 40 of landings, said mechanical means when in registered position being mechanically coupled with their corresponding selector mechanism and operating jointly therewith to cause interception of the first ascending and first descending cars 45 respectively at landings for which up and down calls are registered.

8. In combination, a plurality of elevator cars operating in a bank, car actuated mechanical selector mechanism for each car, a single up and a single down control switch at each of a plurality of landings, mechanical call registering mechanism for all of said cars controlled in common from said single up and a single down control switch to be mechanically coupled to their 50 associated mechanical selector mechanisms to be actuated thereby to cause slow-down of a first car of a bank which is ascending and the first car which is descending, and mechanical call registering mechanism controlled from within each 55 car of the bank to be mechanically coupled with said mechanical selector mechanism which corresponds thereto to cause slow-down only of the individual car from which calls are initiated.

9. In combination, an elevator car, control means therefor comprising mechanical selector actuating mechanism having a linear movable traveler, and camming means to impart a step-by-step movement to said traveler in accordance with pre-determined positions of the car and being adjustable to allow for varying floor heights, and means to adjust said camming means.

10. In combination, an elevator car, control means therefor comprising mechanical selector actuating mechanism having means movable in

- 5 a linear path, and two sets of camming devices to impart step-by-step movements to said means in accordance with pre-determined positions of the car, said devices being independently adjustable as to those comprising each set to allow for varying floor heights and being independently adjustable as between the two sets, and means to adjust said two sets of camming devices.
- 10 11. In combination, an elevator car, control means therefor comprising selector mechanism having means movable in a linear path, two sets of camming devices to impart step-by-step movements to said means in accordance with pre-determined positions of the car, each set being carried by independent shafts, and a driving connection between the car and said shafts.
- 15 12. In combination, an elevator car, control means therefor comprising selector mechanism having linear movable travelers, two sets of camming devices to impart a step-by-step movement to said travelers in accordance with pre-determined positions of the car, said two sets being carried by independent shafts to permit independent adjustment as between the two sets to allow for different sequential operations therebetween as necessary for up and down directions of car movement, and those of each set are adjustable relatively to each other on their respective shafts to allow for varying floor heights, and means to adjust said two sets of camming devices.
- 20 13. In combination, an elevator car, control means therefor comprising a selector mechanism which for each landing comprises a motion transmitting member, and means to actuate said members successively comprising a traveler having step-by-step movement to bring it into relation with said members, and means controlled by the car to move said traveler a predetermined amount only when the car is at predetermined points within its limits of travel, said traveler remaining stationary at all other times during movement of the car between said limits.
- 25 14. In combination, an elevator car, control means therefor comprising a mechanical selector mechanism which for each landing comprises a motion transmitting member, means to actuate said members comprising a pinion, a connection between the car and pinion to rotate same, and means to impart a step-by-step movement to said pinion in accordance with car position to cause same to actuate said motion transmitting members in successive order.
- 30 15. In combination, an elevator car, a pinion, a connection between the car and pinion to rotate same, means to impart a step-by-step movement to said pinion in accordance with pre-determined positions of the car, a control switch at each of a plurality of landings for initiating calls, mechanical means for registering calls in response to operation of said initiating switches, and mechanical selector mechanism comprising a plurality of members, said movement of said pinion bringing it into engagement with said members successively, said mechanical call registering means being controlled selectively to be mechanically coupled to said selector mechanism, and such coupled parts being actuated in successive order by said pinion to cause automatic slow-down of the car when it reaches a pre-determined distance from landings for which calls are registered.
- 35 16. In combination, an elevator car, a control switch at each of a plurality of landings for initiating calls, mechanical means responsive to said
- 40 initiating switches to register calls, mechanical selector mechanism comprising a plurality of members, a rotatable pinion having a step-by-step linear movement to bring it into engagement with said members successively in accordance with pre-determined positions of the car successively to actuate said members, and electrical slow-down mechanism, said mechanical call registering means effective by registration of calls to effect a mechanical coupling together of said slow-down mechanism with said mechanical selector mechanism.
- 45 17. In combination, an elevator car, control mechanism therefor comprising a mechanical selector comprising a plurality of members each having a toothed portion, and a drive for said members comprising an advance and rear pinion to mesh with said toothed portions.
- 50 18. In combination, an elevator car, control mechanism therefor comprising selector mechanism, having a plurality of segmental gears, and a drive for said mechanism comprising a rear and advance pinion, to mesh with said gears and means to impart linear and rotative movements to said pinions.
- 55 19. In combination, an elevator car, means comprising selector mechanism to control same, a drive for said selector mechanism comprising rear and advance pinions, one normally in an operative plane and the other normally in an inoperative plane, and speed controlled means to cause movement of said latter pinion to an operative plane.
- 60 20. In combination, an elevator car, selector mechanism to control the same and having two linear movable members one arranged in advance of the other, a C. E. M. F. device to render said advance member operative, and means dependent on car position to render said advance member inoperative.
- 65 21. In combination, an elevator car, control means therefor comprising a mechanical selector comprising a plurality of independently movable members, means to move same successively in accordance with the position of the car, call registering means comprising a plurality of motion transmitting members, said latter named members and said selector members being normally uncoupled, means to retain said selector members and said transmitting members in such uncoupled relation, said latter means being independent of said selector members, and means operable selectively to effect the coupling together of said transmitting means and their corresponding selector members.
- 70 22. In combination, an elevator car, call registering means comprising a plurality of motion transmitting members, means to actuate said members in accordance with the position of the car, a control switch at each of a plurality of landings operable to shift said transmitting members from a re-set position to a set position for actuation in successive order by said actuating means, a plurality of decelerating switches, and mechanical mechanism common to said transmitting members to be actuated thereby, to cause operation of said decelerating switches successively thereby to cause slow-down of the car in successive steps.
- 75 23. In combination, an elevator car, a car start switch, a plurality of accelerating switches, means controllable only from within the car to initiate operation of said start and accelerating switches, means to maintain all of said switches in operated position automatically, call register-

ing means comprising a plurality of motion transmitting members, mechanical selector mechanism comprising a plurality of car actuated members, a control switch at each of a plurality of landings, a plurality of control switches within the car, one for each of said landings, means responsive to said control means at the landings and within the car to couple said transmitting members with their corresponding selector members, 10 a mechanical member common to said transmitting members to be actuated thereby, and means actuated by said mechanical member to cause operation of said accelerating switches successively to slow the car down in successive steps 15 followed by a subsequent stop operation.

24. In combination, an elevator car, call registering means comprising a plurality of members, mechanical selector mechanism comprising a plurality of movable members, control switches operable selectively to mechanically couple said first named members with corresponding selector members, a plurality of accelerating switches, a member common to said first named members to be actuated thereby, means controlled by said 20 common member to cause operation of said accelerating switches in an order inversely to that in which they initially operate, a drive for said selector members, means to control said drive so that a pre-determined range of movement is imparted to said common member to cause said means controlled by said latter member to cause operation of a pre-determined number of said accelerating switches, and additional means to control said drive so that a greater pre-determined range of movement is imparted to said 25 common member to cause said means controlled thereby to cause operation of all of said accelerating switches.

25. In combination, an elevator car, a mechanical control system therefor comprising a selector comprising a plurality of independently movable members, said members each having a toothed portion, a drive for said members comprising a master pinion whose length is in some proportion 40 to the distance as measured between the two limits of car travel, an additional pinion to mesh with said master pinion and said toothed pinions, and means operable in accordance with car position to shift said additional pinion into mesh 45 with said toothed portions in successive order.

26. In combination, an elevator car, a switch, means to actuate said switch comprising a plurality of toothed members, a master pinion whose length is in some proportion to the distance as measured between the two limits of car travel, an additional pinion to mesh with said toothed members and said master pinion, and means operable in accordance with pre-determined positions of the car to shift said additional pinion 50 into mesh with said toothed members in successive order.

27. In combination, an elevator car, a switch, means to actuate said switch comprising a plurality of toothed members, a master pinion whose length is in some proportion to the distance as measured between the two limits of car travel, an additional pinion to mesh with said toothed members and said master pinion, a linearly movable traveler forming a bearing support for said additional pinion, and means operable in accordance with car position to shift said traveler to cause said pinion to mesh with said toothed portions in successive order.

28. In combination, an elevator car, a selector comprising a plurality of independently movable

members, means to actuate said members comprising a linearly movable traveler, means carried by said traveler to co-act with said members to move same, and means operable in accordance with pre-determined positions of the car to shift said traveler to cause said means carried thereby to cause movement of said members in successive order.

29. In combination, an elevator car, a selector comprising a plurality of movable members, a linearly movable traveler carrying means to co-act with said members to move same, means to impart a step-by-step movement of said traveler to cause said means carried thereby to cause movement of said members in successive order, a plurality of members controlled selectively to be coupled to corresponding selector members for actuation thereby, and a member common to said latter named members to be actuated thereby.

30. In combination, an elevator car, a plurality of movable members each having a toothed portion, a pair of pinions, means to form bearing supports for said pinions so that one is in the rear and the other is in advanced relation, said rear pinion being normally in a plane to mesh with said toothed portions and said advanced pinion being normally in a non-meshing plane with respect to said toothed portions, and means to shift said pinions so that said rear pinion is in a non-meshing plane and said advanced pinion 30 is in a meshing plane with respect to said toothed portions.

31. In combination, an elevator car, a plurality of movable members each having a toothed portion, rear and advanced pinions one normally 35 in a meshing plane and the other in a non-meshing plane with respect to said toothed portions, means to shift said pinions to change their relative planes, a master pinion which is of a length in some proportion to the travel of the car, said 40 two first named pinions in constant mesh with said master pinion, and means operable in accordance with car position to move said rear and advance pinions into meshing relation with said toothed portions successively.

32. In combination, an elevator car, control means therefor comprising a selector having a linear movable member, means to initiate slow-down of the car at different pre-determined distances from a landing, said means comprising two 50 members carried by said linear movable member and arranged in series thereon one in advance of the other, and means operable to render said rear member ineffective and said advance member effective to initiate slow-down of the car.

33. In combination, an elevator car, control means therefor comprising a selector having a linear movable traveler, means to initiate slow-down of the car at different pre-determined distances from a landing, said means comprising two 60 members carried by said traveler and arranged in series thereon one in advance of the other, and a C. E. M. F. device to render said advance member effective to initiate slow-down of the car at the greater of said distances.

34. In combination, an elevator car, control means therefor comprising a selector having a linear movable traveler, means to initiate slow-down at the car at different pre-determined distances from a landing, said means comprising 70 two members carried by said traveler and arranged in series one in advance of the other, a C. E. M. F. device to render said advance member effective to initiate slow-down of the car at the greater of said distances, and means operable 75

subsequently to a pre-determined slow-down operation of the car to render said rear member effective to control further slow-down operation of the car.

5 35. In combination, an elevator car, selector mechanism comprising means movable in accordance with car position, call registering means comprising a plurality of motion transmitting members controlled selectively to be coupled mechanically to said movable selector means for actuation thereby in successive order, a traveling brush actuated in common by said transmitting members, a plurality of segments arranged to be engaged in successive order by said brush, and a plurality of slow-down circuits controlled by said brush and segments.

10 36. In combination, an elevator car, selector mechanism comprising means movable in accordance with car position, call registering means comprising a plurality of motion transmitting members controlled selectively to be mechanically coupled to said movable selector means for actuation thereby in successive order, a pair of traveling brushes one in advance of the other, actuated in common by said transmitting members, a plurality of segments certain of which are engageable in successive order by one of said brushes and all of said segments being engageable in successive order by the other of said brushes, a plurality of decelerating switches controlled by said brushes and segments, and a C. E. M. F. device to render said brush which engages all of said segments effective.

15 37. In combination, an elevator car, a selector mechanism comprising a plurality of movable members, a linear movable traveler having means to coact with said members to cause movement thereof, means to impart a step-by-step movement to said traveler to cause said coacting means to move said selector members in successive order, and a Selsyn drive to actuate said last named means in accordance with movement of the car.

20 38. In combination, an elevator car, control means to initiate slow-down of the car at different pre-determined distances from a landing said means comprising a pair of traveling brushes arranged in series one in advance of the other, segments arranged to be engaged in successive order by said brushes, a counter electro-motive-force device effective to render said advance brush effective to initiate slow-down of the car at the greater distance from said landing, and means controlled by said counter-electro-motive-force device to render said rear brush ineffective.

25 39. In combination, a plurality of cars, and means to register a call common to all cars, to intercept the first of said cars at the landing for which said call is registered and whose direction of movement corresponds to such registered call, said means comprising a control switch at the landing, to initiate the call, and a plurality of motion transmitting members, one for each of said cars, normally in re-set position and all being controlled in common by said control switch to be moved to a set or call registering position in response to operation of said control switch.

30 40. In combination, a plurality of cars, and means to register a call common to all cars, to intercept the first of said cars at the landing for which said call is registered and whose direction of movement corresponds to such registered call, said means comprising a manual control at the landing to initiate the call, a plurality of motion transmitting members, one for each of said cars, normally in a re-set position, and an electro-

magnet common to all of said transmitting members and responsive to operation of said manual control to cause movement of all of said transmitting members to a set or call registering position.

5 41. In combination, a plurality of cars, and means to register a call common to all cars, to intercept the first of said cars at the landing for which said call is registered and whose direction of movement corresponds to such registered call, said means comprising a control switch at the landing to initiate the call, a plurality of motion transmitting members, one for each of said cars, a trip controlled member common to all of said transmitting members to retain them in re-set position, and trip releasing means responsive to operation of said control switch to release said common member to permit movement of all of said transmitting members to a set or call registering position.

10 42. In combination, a plurality of cars, means to register a call common to all cars, to intercept the first of said cars at the landing for which said call is registered and whose direction of movement corresponds to such registered call, said means comprising a control switch at the landing to initiate said common call, a plurality of motion transmitting members, one for each of said cars, normally in re-set position and all being controlled in common by said control switch to be moved to a set or call registering position in response to operation of said control switch, and a plurality of car actuated selector members, one for each of said cars, each of said transmitting members when in said call registering position being mechanically coupled to said selector members which correspond thereto for actuation thereby.

15 43. In combination, a plurality of cars, an up control switch at a landing to control an up going car, a down control switch at said landing to control a down going car, a plurality of motion transmitting members, one for each of said cars, controlled in common to register a call in response to operation of said up control switch, and an additional plurality of motion transmitting members one for each of said cars, controlled in common to register a call in response to operation of said down control switch.

20 44. In combination, a plurality of cars, an up control switch at a landing, a down control switch at said landing, a plurality of up car actuated selector members, one for each of said cars, a plurality of motion transmitting members, one for each of said cars, controlled in common by said up control switch each to be mechanically coupled to corresponding selector members, a plurality of down car actuated selector members, one for each of said cars, and additional plurality of motion transmitting members, one for each of said cars, controlled in common by said down control switch each to be mechanically coupled to corresponding down selector members.

25 45. In combination, a plurality of cars operating in a bank, a plurality of up control switches, one for each of a plurality of landings, a plurality of down control switches, one for each of said landings, a plurality of motion transmitting members for each landing, one for each car of the bank, controlled in common to register a call common to all cars of the bank in response to operation of the up control switch for the landing corresponding thereto, a plurality of selector members for each landing, one for each car of the bank, each being mechanically coupled to its

corresponding transmitting member when in call registering position, an additional plurality of motion transmitting members for each landing, one for each car of the bank, controlled in common to register a call common to all cars of the bank in response to operation of the down control switch for the landing corresponding thereto, and an additional plurality of selector members for each landing, one for each car of the bank, each being mechanically coupled to its corresponding additional transmitting member when in call registering position.

46. In combination, an elevator car, up and down control switches at said landing, a motion transmitting member responsive to operation of said up control switch to register the call, an additional motion transmitting member responsive to operation of said down control means to register the call, a selector member mechanically coupled to said motion transmitting member when in call registering position, and an additional selector member mechanically coupled to said additional motion transmitting member when in call registering position.

47. In combination, an elevator car, up and down control means at a landing to initiate calls therefrom, a motion transmitting member normally in re-set position, an electro-magnet responsive to said up control means to cause movement of said transmitting member to call registering position, an additional motion transmitting member normally in re-set position, and an additional electro-magnet responsive to said down control means to cause movement of said latter member to registering position.

48. In combination, an elevator car, up and down control means at each of a plurality of landings, up and down motion transmitting members for each of said landings, normally in re-set position, up and down electro-magnets for each of said landings responsive to corresponding up and down control means to cause corresponding motion transmitting members to register calls, means within the car to register calls for each of said landings, and floor selector mechanism operable when the car is going up to mechanically actuate said up transmitting members which are in call registering position to cause stop of the car at landings for which calls are registered, and operable when the car is going down to mechanically actuate said down transmitting members which are in call registering position to cause stop of the car at landings for which down calls are registered, said up and down stops being made in the natural order of landings regardless of the order in which the calls are registered.

49. In combination, an elevator car, up and down control means at each of a plurality of landings, up and down motion transmitting members for each of said landings, normally in re-set position, up and down electro-magnets for each of said landings responsive to corresponding up and down control means to cause corresponding motion transmitting members to register calls, a plurality of decelerating switches, a member common to said up transmitting members to control the operation of said decelerating switches when the car is going up, an additional member common to said down transmitting members to control operation of said decelerating switches when the car is going down, and selector mechanism operable in accordance with the position of the car when it is going up to actuate said up transmitting members with are in call registering position, in successive order thereby causing said

decelerating switches to slow-down the car at landings for which calls are registered, in the natural order of the landings regardless of the order in which said calls are registered, said selector mechanism operable in accordance with the position of the car when it is going down to actuate said down transmitting members which are in call registering position, in successive order thereby causing said decelerating switches to slow-down the car at landings for which down calls are registered, in the natural order of the landings regardless of the order in which said calls are registered.

50. In combination, an elevator car, a control switch at a landing to initiate a call, a car actuated selector member, and a motion transmitting member normally in re-set position out of coupled relation with said selector member and controlled by said control switch to be mechanically coupled to said selector member without moving said latter member.

51. In combination, an elevator car, manual control means at a landing to initiate a call, a car actuated selector member, a motion transmitting member, means independent of said selector member to retain said transmitting member in re-set position, and an electro-magnet having a circuit responsive to said manual control means, to actuate said retaining means to cause movement of said transmitting member into coupled engagement with said selector member for actuation thereby.

52. In combination, an elevator car, control means at a landing, car actuated selector mechanism which for said landing comprises two independently movable members, up and down motion transmitting members, normally in re-set position, and means responsive to operation of said control means to cause said up transmitting member and one of said selector members to be mechanically coupled together and to cause said down transmitting member and the other of said selector members to be mechanically coupled together.

53. In combination, an elevator car, selector mechanism comprising means movable in accordance with car position, call registering means comprising a plurality of motion transmitting members controlled selectively to be mechanically coupled to said movable selector means for actuation thereby in successive order, a pair of travelling brushes one in advance of the other, actuated in common by said transmitting members, a plurality of segments certain of which are engageable in successive order by one of said brushes and all of which are engageable in successive order by the other of said brushes, a plurality of switches controlled by said brushes and segments, driving means for said selector effective when the car in its advance toward any given landing is a pre-determined distance therefrom and on condition that a call is registered for such landing, to actuate the transmitting member corresponding thereto to impart a pre-determined range of movement to said brushes, and additional driving means for said selector mechanism effective when the car in its advance toward said given landing and on condition that a call is registered for said landing, is a pre-determined distance greater than said first named pre-determined distance from said landing, to actuate the transmitting member corresponding to said landing to impart movement to said brushes, said additional drive imparting a predetermined range of movement to said brushes which is followed by operation of said

- first named drive to continue movement of said brushes the result being to cause one of said brushes to engage all of said segments to control all of said switches to operate in successive order 5 to decelerate the car from a maximum speed, in successive steps.
54. In combination, a plurality of elevator cars, a control switch at a landing to initiate a call, a plurality of motion transmitting members, one 10 for each of said cars controlled in common by said control switch to register a call common to all of said cars, a plurality of movable selector members, one for each of said cars, said selector members being grouped relatively close together to be 15 mechanically coupled to their corresponding transmitting members, and a plurality of Selsyn drives, one for each car to actuate its associated selector members in accordance with the position of the car.
- 20 55. In combination, a plurality of elevator cars, a manual control means at a landing to initiate a call, a plurality of motion transmitting members, one for each of said cars, an electro-magnet common to all of said transmitting members, responsive 25 to said manual control means to cause movement of all of said transmitting members to call registering position, a plurality of movable selector members, one for each of said cars, said selector members being grouped relatively close together in off-set relation to be mechanically coupled to their corresponding transmitting members, and a plurality of Selsyn drives, one for each car to actuate its associated selector member in accordance with the position of the car.
- 30 56. In combination, a plurality of cars, up and down switches at each of a plurality of landings, a plurality of motion transmitting members which for each landing comprise one up and one down member for each car, all up members and all down members for each landing being controlled in common by said up and down switches respectively at the landing, a plurality of selector members which for each landing comprise one up and one down member for each car, said up members for all cars and all landings being grouped relatively close together to form an up group, said down members being likewise grouped to form a down group, and a plurality of Selsyn drives one for each car to actuate its associated selector members in accordance with the position of the car.
- 35 57. In combination, a plurality of elevator cars, a control switch at a landing, a plurality of motion transmitting members, one for each of said cars, an electro-magnet common to all of said transmitting members, responsive to said control switch to cause movement of all of said transmitting members to call registering position, a plurality of movable selector members, one for each 40 of said cars, said selector members being grouped relatively close together to be mechanically coupled to their corresponding transmitting members when in said call registering position.
- 45 58. In combination, a plurality of cars, up and down control switches at each of a plurality of landings, a plurality of motion transmitting members which for each landing comprise one up and one down member for each car, all up and all down members for each landing being controlled in common by said up and down control switches respectively at the landing, a plurality of selector members which for each landing comprise one up and one down member for each car, said up selector members for any one car and for all landings being arranged in a row there being as many up 50 rows as there are cars, all of said rows being grouped relatively close together in off-set relation as viewed from one direction, and those for any one landing being closely grouped together and in staggered relation as viewed from another direction so that each is mechanically coupled to its corresponding up transmitting member when in call registering position, said down selector members being likewise arranged so that each is mechanically coupled to its corresponding down transmitting member when in call registering position.
- 55 59. In combination, a plurality of cars, up and down control switches at each of a plurality of landings, a plurality of motion transmitting members which for each landing comprise one up and one down member for each car, all up and all down members for each landing being controlled in common by said up and down control switches respectively at the landing, a plurality of selector members which for each landing comprise one up and one down member for each car, said up selector members for any one car and for all landings being arranged in a row there being as many up rows as there are cars, all of said rows being grouped relatively close together in off-set relation as viewed from one direction, and those for any one landing being closely grouped together and in staggered relation as viewed from another direction so that each is mechanically coupled to its corresponding up transmitting member when in call registering position, said down selector members being likewise arranged so that each is mechanically coupled to its corresponding down transmitting member when in call registering position.
- 60 60. In combination, an elevator car, means controllable from within the car to initiate a plurality of calls, a car actuated mechanical selector, a plurality of motion transmitting members, normally in re-set position, means responsive to said first named means operable selectively thereby to mechanically couple said members to said selector for actuation thereby in successive order, and means controllable by the car at a pre-determined point in its travel to uncouple all of such coupled members, thereby to cancel all registered calls.
- 65 61. In combination, an elevator car, a plurality of controls within the car, one for each of a plurality of landings, a plurality of motion transmitting members, one up and one down member for each landing, a plurality of selector members, one up and one down for each landing, and means responsive to each one of said controls to mechanically couple both the up and down transmitting members for the landing which corresponds thereto, to corresponding selector members for actuation thereby.
- 66 62. In combination, a plurality of cars, a control switch at a landing to initiate a call, a plurality of motion transmitting members common to said control switch and responsive thereto to register a call common to all of said cars, to intercept the first of said cars to approach said landing, means controlled by said first car to re-set said common registering means, and means to prevent said common registering means from registering a second call in response to said con- 70 75

trol switch until re-start of said first car from said landing.

63. In combination, a plurality of cars, a control switch at a landing, a plurality of motion transmitting members, a member common to said members to retain them in re-set position and responsive to said control switch to release said members to move to a call registering position thereby to register a call common to all of said cars, and means to prevent said common member from releasing said transmitting members to register a second call common to all cars until the car which is intercepted in response to said first call re-starts from said landing.

15 64. In combination, a plurality of cars, a control switch at a landing, means to cause slow-down of a first car to reach a pre-determined distance from said landing in response to operation of said control switch, said means comprising a plurality of motion transmitting members, one for each of said cars, means common to said members to retain them in re-set position and responsive to said control switch to release said members to assume call registering position, 20 means effective when slow-down is initiated automatically to re-set said common registering means, and means to prevent registration of a second common call until re-start of said first car from said landing.

25 65. In combination, an elevator car, means to control same comprising a selector having means movable in a linear path, and means to impart a step-by-step movement to said traveler in a linear path, said means comprising a rotatable shaft, up and down camming members, and arms rotatable with said shaft and supporting said up and down camming members for independent adjustment thereon.

30 66. In combination, an elevator car, means to control same comprising a selector having movable means, and means to impart a step-by-step movement to said movable means in a linear path, said means comprising for each of a plurality of landings, one up and one down rotatable cam, anti-friction means carried by said movable means, and each cam having parallel camming members separated by a slot between which said anti-friction means is adapted to pass so that rotation of said up and down cams in one direction causes one of said camming members for each cam to co-act with said anti-friction means thereby to impart a relatively quick and relatively short range of movement to said movable means in one direction, and rotation of said cams in a reverse direction causes the other of said camming members for each cam to co-act with said anti-friction means thereby to impart a relatively quick and relatively short range of movement to said movable means in a reverse direction to said above direction, and means to adjust said cams.

35 67. In combination, an elevator car, means to control same comprising a selector having a traveler, and means to impart a step-by-step movement to said traveler in a linear path, said means comprising a series of camming members each having a pair of parallel sides separated by a slot, said series of members as a unit forming a sectional helix, a rotary shaft, and an arm adjustably to support each camming member for rotation by said shaft.

40 68. In combination, a plurality of cars, a single up and a single down control means at each of a plurality of landings, a plurality of motion transmitting members comprising for each of

5 said landings one up and one down member for each of said cars, said up members for any landing and said down members for any landing controllable in common by said up and down control means for the corresponding landing, thereby to register an up call common to all of said cars and to register a down call common to said cars, car control switches which for each car comprise a start switch and a plurality of accelerating switches, a car actuated selector mechanism for each car to mechanically actuate its associated up transmitting members which are in registered position, in successive order when the car is going up, and to mechanically actuate its associated down transmitting members which are in registered position, in successive order when the car is going down, a member for each car common to its associated up members, another member common to its associated down members, means controlled by said up and down common members for each car to control said control switches to cause deceleration of the car in successive steps followed by final stop, and means to cause said common members to initiate said deceleration operation at different pre-determined distances from any given landing, so that for the shorter distance the deceleration operation is initiated while the car is moving at an intermediate rate of speed and for the longer distance the deceleration operation is initiated while the car is moving at a maximum rate of speed.

20 69. In combination, an elevator car, call registering means comprising a plurality of motion transmitting members, selector mechanism actuated in accordance with position of the car, control switches operable selectively to cause movement of said motion transmitting members from a re-set to a set position for actuation in successive order by said selector mechanism, a plurality 25 of decelerating switches, actuated in common by said motion transmitting members, means to cause said selector mechanism to initiate movement of any given motion transmitting member which is in call registering position, when the car in its approach to the landing corresponding thereto is a pre-determined distance therefrom, thereby to cause operation of certain of said decelerating switches to slow the car down in successive steps, said slow-down operation being initiated when the car is travelling at a certain intermediate speed, and means to cause said selector mechanism to initiate movement of any given motion transmitting member which is in call registering position, when the car in its approach to the landing corresponding thereto is at a pre-determined distance therefrom greater than said first named pre-determined distance, thereby to cause operation of all of said decelerating switches to slow the car down in successive steps said operation being initiated when the car is travelling at its maximum speed.

30 70. In combination, an elevator car, call registering means comprising a plurality of independently movable motion transmitting members, and means operable in accordance with car position to actuate said members in successive order, said means comprising two actuating members, one effective to actuate any given member when the car in its approach to the landing corresponding to said given member is a pre-determined distance from said landing, and the other effective to actuate said given member when the car in its approach to said landing is

a pre-determined distance therefrom greater than said first named pre-determined distance.

5 71. In combination, an elevator car, call registering means comprising a plurality of independently movable motion transmitting members, means operable in accordance with car position to actuate said members in successive order, said means comprising two actuating members, one effective to actuate any given member when the car in its approach to the landing corresponding thereto is a pre-determined distance therefrom, and the other effective to actuate said given member when the car in its approach to said landing is a predetermined distance therefrom greater than said first named pre-determined distance, and means to render said actuating members effective one at a time.

10 72. In combination, an elevator car, call registering means comprising a plurality of independently movable motion transmitting members, means to actuate said members, said means comprising a plurality of members operable in accordance with car position and in successive order to actuate each of said members, and a plurality of decelerating switches all common to each of said motion transmitting members and controllable thereby to operate in successive order.

15 73. In combination, an elevator car, means to control same comprising a plurality of independently movable motion transmitting members, means to actuate said members in successive order, said means comprising two members

one in advance of the other and operable in accordance with position of the car, and means to render said advance member effective, said member being normally ineffective.

20 74. In combination, an elevator car, a plurality of independently movable members, one for each of a plurality of landings, and means operable in accordance with car position to actuate said members, said means comprising two actuating members common to all of said first 10 named members, and operating successively to actuate each of said latter members.

25 75. In combination, an elevator car, and a control system therefor comprising, a slow-down switch, a control switch at each of a plurality of landings, a plurality of movable mechanical members, one for each of said landings, normally in a reset position and responsive to its corresponding control switch to move to a registering position thereby to register the call, car actuated 20 mechanical selector mechanism, said mechanical call registering members when in said registering position coacting directly with said mechanical selector mechanism to cause mechanical actuation of said slow-down switch to slow-down 25 the car when it is at pre-determined distances from landings for which said members register calls, and means independent of said mechanical selector mechanism to retain said movable mechanical call registering members in said reset 30 position or non call registering position.

ERNEST L. GALE.
